ATTORNEY.

UNITED STATES PATENT OFFICE.

MICHAEL B. SPINELLE, OF CHICAGO, ILLINOIS, ASSIGNEE OF ONE-HALF TO JOSEPH F. CARSON, OF CHICAGO, ILLINOIS.

BALL-JOINT FAUCET.

Application filed January 13, 1928. Serial No. 248,513.

The present invention relates to valve construction in general but more particularly to ball valves, and has for its main object to provide such a valve that will not leak even 5 after hard and long usage.

It is a well known fact that faucets, for instance in bathrooms, kitchen sinks, or the like, and especially those for hot water, in a short time start to leak from corrosion and 10 wear. This is caused mostly by the sediments and grit deposited in or near the valve seat, so that when the valve is opened or closed the grit scars the seat and tears the packing, the latter being still more weakened by the 15 exposure to the hot water.

In order to overcome this the present invention contemplates an all metal valve without fiber or leather packings in the seat or on the valve piston. Instead of its efficiency 20 being diminished by long use, this valve tends to obtain, if possible, a firmer and tighter seating from the constant grinding of the contacting surfaces.

Another object of the invention is to construct the valve as simply as possible by using 25 the smallest number of parts which are easily fitted together with a minimum amount of machine work. In other words, it can be produced at a very small cost, with little labor. 30 It is accordingly very economic, which coupled with its great efficiency and enduring qualities, makes it a desirable article for use and manufacture and of considerable improvement over existing valves of this class.

The valve body or casing is provided with 35 a very simple union or closure around the valve stem at the top. Instead of using several pieces for this, the present invention has a single piece namely a cap threaded in 40 the body and also provided with internal threads for advancing and retracting the valve piston.

Moreover, the packing box for the valve stem consists of a screw plug or gland recessed and threaded in the cap, and an asbestos packing or gasket pressed by the plug 45 tightly around the valve stem.

In the accompanying drawing one embodiment of the present invention is illustrated: and

Figure 1 shows the faucet in vertical section;

Figure 2 a view of some of the details, partly in elevation and partly in section;

Figure 3 is a top plan view of one of the 55 details in Figure 2;

Figures 4 and 5 enlarged views of another detail in vertical section and top plan view, respectively; and

Figures 6 and 7, also enlarged views, show 60 vertical and horizontal sections, respectively, of the valve spindle and head.

In the drawing the reference characters designate corresponding members in the several views and numeral 10 represents the 65 valve housing of a faucet or spigot having the usual outlet or spout 11 and a hollow threaded shank 12 for securing it in position. A shoulder 13 is formed on the shank constituting a stop against the basin on which it 70 is used. A valve chamber 14 is formed at the juncture of the spout and the shank and this chamber terminates with a throat-like upward extension 15 which is threaded internally as at 16 to receive the cap 17 which has 75 a hexagonal or other polygonal collar 18 for tightening the cap in place by the use of a suitable tool. The exterior portion of the throat 15 is also flattened in a similar manner for screwing down the faucet in place.

In the upper end of the cap is provided a packing box with a packing 19 preferably consisting of asbestos fabric enclosing the valve stem or spindle 20 and pressed against the same by a gland 21 threaded in the cap 17 and terminating with a hexagonal or other flat edged collar 22 for screwing it down tight. The inner or lower edge 23 is inwardly bevelled to force the packing 19 80 against the valve stem 20.

The chamber 14 has a bottom 24 with a passage 25 communicating with the hollow portion 26 of the shank 12, permitting the water or other fluid to pass from its source through the chamber 14 and out of the spout 11. This 85 passage 25 is threaded to receive the metallic valve seat 27 which is drawn up tight with its collar 28 in the bottom by means of any flat tool engaging in the slots 39 which extend outwardly from the narrow central opening 30. This opening is enlarged in diameter at its upper end to provide a circular seating edge 31 for the valve piston.

The valve piston consists of only two parts, namely the shank 20 and the valve head 100 which is a hardened steel ball 32 permanently secured together to form a unit. For this reason the stem, which is made out of metal

stock, preferably brass, is recessed at its inner or lower end as at 33 to receive the ball 32 which is preferably treated with so-called "colonial plating" that will not rust. The recess is slightly deeper as well as slightly greater in diameter than the ball 32. After the shank end has been counterbored and the ball inserted the edge 34 is spun around the ball until it is contracted to less than the ball 10 diameter. In this manner a ball chamber is provided which permits of a limited axial movement of the ball in the shank end but still retains the ball permanently therein. There being next to no wear on the edge 34, 15 the ball will be retained indefinitely in the shank end, because the edge 34 never comes in contact with the ball except during assembling of the parts as the water pressure will always press the ball against the bottom of the recess 33 directly the faucet has been installed and is in use.

The shank 20 has a narrow neck 35 above the recessed end and is provided with a flat-threaded portion 36 adapted to engage in a 25 correspondingly threaded portion 37 in the cap 17, in order to advance or retract the ball to or from its seat 31. The upper or outer end 38 of the shank 20 is tapered and preferably of square cross section adapted to fit 30 snugly in a corresponding aperture formed in the handle 39 which is retained in position on the shank by a screw 40 or in any other suitable manner.

When assembled as indicated in Figure 1 35 of the drawing the valve is seated by screwing down the shank 20 until the ball 32 rests on the seat edge 31. The bottom of the recess 33 then presses hard against the ball 32 which in turn rests firmly on the seat edge 31, while the crimped or contracted rim or edge 34 40 stands free of the ball. As the ball engages the circular seat edge 31 a perfectly tight joint is formed which will not leak. In time this seat may become slightly flattened or 45 rather bevelled, but as it then conforms exactly to the contour of the ball, no water can pass. Nor will corrosion effect the valve, because every time the valve is opened or closed a slight grinding of the seat by the ball will 50 take place from the turning of the valve stem, so that the contacting surfaces will always be shiny and well polished.

When the valve stem is screwed up to open 55 the valve, the ball 32 will still remain pressed against the bottom of the recess 33 and remain free from the circular rim 34, because the water pressure always acts to lift the ball.

Accordingly, there will be next to no wear on said rim.

The simplicity of this valve construction is 60 evident when it is considered that the valve head and stem here consist of only two parts and they forming a permanent unit, while ordinarily three or four pieces are utilized for this purpose. Likewise, the upper closure of 65 the valve body including the packing box here consists of only three parts, while no less than five is the usual number in ordinary constructions. Furthermore, all the loose parts are made from round or hexagonal stock and no 70 machining is necessary on the body except on contacting surfaces, all other surfaces being rough as cast and the whole ultimately nickel plated.

It is to be understood that the invention is 75 not limited to the details of construction here shown and disclosed but that these may be varied widely without departing from the spirit of the invention as defined by the 80 claims.

What I claim as new is:

1. In a valve construction the combination with a housing having a valve seat; of a cap threaded in the housing, a two-piece valve member comprising a stem and a ball loosely 85 secured therein, said stem being axially movable in the cap to seat the valve ball, a packing box in the cap, a packing element and a gland adapted to press the packing element around the valve stem; said valve seat including an annular member threaded in the housing and provided with a cross-shaped aperture forming a fluid passage therethrough.

2. In a valve construction the combination with a housing having a valve seat, of a cap 95 secured in the housing, a two-piece valve member comprising a stem and a ball, the stem being threaded in the cap to seat the ball, a recess being provided in the end of the stem and a rim formed around the mouth of 100 the recess to permanently but loosely secure the ball in the recess; a packing box on the cap, a packing element and a gland adapted to press the packing element around the valve stem, said valve seat including an annular 105 member threaded in the housing and provided with a cross-shaped aperture forming a fluid passage therethrough.

In witness whereof, I have hereunto set my hand at Washington, District of Columbia, 110 this ninth day of December, A. D. nineteen hundred and twenty-seven.

MICHAEL B. SPINELLE.
